(57) **CLAIM**

The ornamental design for a liner for a paint tray, as shown and described.

DESCRIPTION

FIG. 1 is an isometric view thereof;

FIG. 2 is a side view thereof, as taken from the left (unseen) side of FIG. 1;

FIG. 3 is a side view thereof, as taken from the right side of FIG. 1 (the side views are mirror images of one another);

FIG. 4 is a front end view thereof;

FIG. 5 is a rear end view thereof;

FIG. 6 is a top view thereof; and,

FIG. 7 is a bottom view thereof.

The broken lines in FIGS. 1-7 are for illustrative purposes only and form no part of the claimed design.

UNITED STATES PATENT AND TRADEMARK OFFICE
Certificate

Patent No. D. 619,319 S

Patented: July 6, 2010

On petition requesting issuance of a certificate for correction of inventorship pursuant to 35 U.S.C. 256, it has been found that the above identified patent, through error and without any deceptive intent, improperly sets forth the inventorship.

Accordingly, it is hereby certified that the correct inventorship of this patent is: Mark W. Bergman, Minnetonka, MN (US); Christopher M. Bergman, Hopkins, MN (US); Matthew V. Leyden, St. Paul, MN (US); Jeffrey B. Waffensmith, North Oaks, MN (US); and Jeffrey T. Given, St. Paul, MN (US).

Signed and Sealed this Second Day of July 2013.
